DESIGN FOR A FLOWER CONTAINER

Richard Gottlieb Block, Los Angeles, Calif.

Application January 6, 1940, Serial No. 89,338

Term of patent 7 years

o all whom it may concern:

Be it known that I, Richard Gottlieb Block, a citizen of the United States of America, residing in the city and county of Los Angeles, in the state of California, have invented a new, original, and ornamental Design for a Flower Container, which the following is a specification, reference being had to the accompanying drawing forming part thereof. Figure 1 is a side eleva-

I claim:

The ornamental design for a flower container, as shown.
